CLAIM

The ornamental design for a combined drink straw with integral spoon, as shown and described.

DESCRIPTION

FIG. 1 is a front elevational plan view of a combined drink straw with integral spoon showing my new design thereof; FIG. 2 is a side elevational plan view of the combined drink straw with integral spoon thereof;

FIG. 3 is a rear elevational plan view thereof;

FIG. 4 is a bottom elevational plan view thereof;

FIG. 5 is a top elevational plan view thereof;

FIG. 6 is another modified front elevational plan view of the combined drink straw with integral spoon showing my design as variated from FIG. 1 thereof;

FIG. 7 is a side elevational plan view of the combined drink straw with integral spoon thereof;

FIG. 8 is a rear elevational plan view thereof.

FIG. 9 is a top elevational plan view thereof; and,

FIG. 10 is a bottom elevational plan view thereof.
